Attorney.

UNITED STATES PATENT OFFICE.

FAYE A. MEEKER, OF UTICA, NEW YORK.

CONTROL FOR ENGINE STARTERS.

Application filed November 16, 1925. Serial No. 69,531.

This invention relates to means for controlling the starting of internal combustion engines, particularly of the type employed for propelling automobiles that are equipped 5 with the well-known self-starters.

The primary object of the invention is to provide novel and simple mechanical means for preventing the operation of the self-starter except when the "spark" is retarded, 10 for obviating the danger of the engine back-firing. A further object is to provide a split hollow body, between the sections of which is clamped a relatively limp and flexible diaphragm, with which is associated a locking 15 bolt, the latter being reciprocated by parts having direct connection with the lever that controls the timer, and by which the spark may be advanced or retarded by the driver, at will, in a well-known manner; the said 20 body preferably being mounted upon or adjacent the self-starter, and the locking bolt being movable across the path of the primary starting members, as for example, the usual starting lever common to self-starters, 25 for preventing the operation of the starter, in case the timer lever is set for advancing the spark. And a further object is to provide means for releasing the locking bolt and for holding the said bolt inoperative as long 30 as the timer lever is left in the spark retarding position.

This invention relates to improvements in the safety device shown and described in my pending application, Serial Number 69,532, 35 filed November 16, 1925.

The various features and parts of the invention will be understood from the detailed description which follows, and by reference to the accompanying drawing, in which—

40 Figure 1 is a broken side elevation of an internal combustion engine equipped with a self-starter, to which my safety device is applied; the latter being indicated by broken lines. Fig. 2 is an enlarged rear-end elevation of the stopping device, showing the bell-crank that controls the locking movements of the bolt. Fig. 3 is an enlarged detached side view of the self-starter in connection with a portion of the auxiliary gear case, 45 and a rear-end view of my device. Fig. 4 is a top-plan view of the locking device illustrated in Fig. 5, showing the bell-crank in the released and operated position. Fig. 5 is a front end view of the same. Fig. 6 is an 50 enlarged top-plan view of the parts shown

in Fig. 3, the full lines showing the locking bolt and related parts in the idle position. And Fig. 7 is a vertical longitudinal section, taken on line 7—7 of Fig. 5, showing the tension means for holding the locking bolt 60 in the released position; also showing the means for projecting the bolt across the path of the starting lever by the operation of the ignition retarding mechanism.

In the drawing, 2 represents generally an internal combustion engine of a well-known type, 3 the main gear casing, and 3' the portion of the casing that usually houses the shiftable starting gear, by which the engine is set in motion by a starter 4. The starter 4 may be of any suitable design or make, and usually comprises an inclosed electric motor (not shown), which in the present case is controlled by a switch member 4'. 5 represents the primary starting lever, which is pivoted to the starter casing by a bolt 5', and is movable in the path of and operates the switch member 4' by means of a rod 5", by the depressing of a pedal 5". In practice, 70 the pedal 5" is usually disposed beneath the dash of the automobile, and is depressed by the driver's foot, for starting the engine. The lower end of the lever 5 usually extends into the casing 3' and shifts the starting gear or pinion in a well-known manner, into and out of mesh with the main gear, which connects with the crank-shaft of the engine. In Figs. 1 and 6, the full lines show the lever 5 and related parts in the released position. The inclined dotted lines in Fig. 3 indicate 75 the operated position of said lever.

80 My self-starter controlling mechanism comprises a split hollow body, consisting of similar concave sections 6—6', between which is disposed a relatively limp and flexible diaphragm 7, preferably made of leather, which is held in place by bolts 6", that pass through the sections 6—6' and tightly clamp said parts together, as shown 85 in Figs. 4, 5 and 7. The diaphragm 7 divides the interior of the body into chambers 6"—6", the former being vented by means of a pipe 8, and the latter chamber being vented by an opening 8', for facilitating the flexing of the diaphragm. Sections 6—6' are bored axially to receive a reciprocable locking bolt 9, whose opposite ends 90 preferably extend beyond the outer faces of the sections. The bolt 9 is preferably formed with a medial flange 9', which over-

lays one face of the diaphragm, to which it is rigidly clamped by bolts 7^a. A reinforcing disc 9^a is mounted upon the reverse face of the diaphragm and is also held in place by the bolts 7^a. When the bolt 9 is in the released position shown in Figs. 1 and 6, its forward end 9^b is preferably positioned a small fraction of an inch forwardly and clear of the starting lever 5 (see Figs. 10 and 7), in readiness at the slightest outward movement or thrust of the bolt, to be projected across the path of the said lever, for preventing its movement towards the switch member 4', by the depressing of the 15 pedal 5^a. The bolt 9 is moved in the direction for intercepting or locking the lever 5, by means of a bell-crank 10, which is pivoted between lugs 10', by a pin 10^a. This movement of the bolt 9 correspondingly flexes the diaphragm 7, as shown by dotted lines in Fig. 7. The bolt and diaphragm are moved in the opposite direction, for freeing the lever 5, by a spring 12, which is carried by said bolt; the said spring 20 being supported and maintained at suitable tension by the flange 9' and the end wall of the section 6 of the body, as best seen in Fig. 7. The bell-crank 10 is so disposed that the arm 10^c normally bears against the projecting rear-end of the bolt 9, when the parts are in the released position (see full lines Figs. 4 and 6). The bell-crank is rocked towards and away from the bolt, by means of a rod 13, one end of which is 25 pivoted to the arm 10^d of the bell-crank, while its other end is pivoted to the operating lever, as 14', of the usual timer 14, as shown in Fig. 1. The bell-crank is arranged to be rocked in the plane of the 30 axis of the bolt 9, and during the locking operation its arm 10^c forces and holds end 9^b of the bolt extended between the switch member 4' and the lever 5, against the tension of spring 12. The timer 14 may be of 35 any suitable make, and according to the showing in Fig. 1, the lever 14' is moved towards the left and right for retarding and advancing the ignition, by means of a rockable connection 15, which connects with 40 the lever 14' by a rod or link 15'. The connection 15 is usually operated by a lever carried by the steering-wheel (not shown) in a well-known manner. The full lines in Figs. 1, 3, 4 and 7 show the lever 14', the 45 bell-crank 10 and related parts, in position for retarding the spark, and when the said parts are so positioned, the driver of the automobile may depress the pedal 5^a and rock the lever 5 in the direction for starting the engine, without any interference by my locking device. When, however, the lever 14' of the timer, and the bell-crank 10 are shifted to the dotted positions shown in Figs. 1, 2, 4 and 7, and to the full line 50 position of Fig. 6, the bolt 9 is disposed

across the path of the lever 5 and prevents the operation of the starter 4, until the driver retards the spark, as explained.

The safety device of my pending application has for its object to prevent the stripping of the starting gears by the operation of the self-starter while the engine is running, and is controlled automatically by vacuum created by the engine pistons, through a suitable connection, as pipe 8, 70 that provides unrestricted communication between the body of the device and the intake manifold, indicated at 16 in Fig. 1, and wherein the said vacuum tends to move and hold the locking bolt across the path 75 of the starter lever, as long as the engine is running. It is obvious that the said means for actuating the locking bolt by vacuum of my pending application and the independent means for operating the said bolt 80 shown and described herein, may be combined in a single device, as shown in Fig. 1, and each of said means may perform its functions without interference from the other actuating means. 90

Having thus described my invention, what I claim, is—

1. A device to prevent starting of an internal combustion engine when the ignition controlling mechanism is set for advancing the spark, comprising a hollow body disposed adjacent the self-starter, a locking bolt reciprocable in and through said body adapted to be automatically moved across the path of the self-starter lever when the ignition controlling means is moved for advancing the spark and tension means to move said bolt out of engagement with the starting lever when the spark is retarded. 100

2. A device for controlling the starting of engines including a self-starter lever, a hollow body disposed adjacent the starter lever, automatic locking means reciprocable in and through said body across the path of the starter lever to prevent operation of the same when the ignition spark is advanced, means to prevent operation of the lever when the engine is running and means for releasing the locking means when the ignition spark is retarded to start the engine. 110

3. A device of the character described, including a self-starter lever and an ignition controlling lever, locking means disposed between said levers adapted to move across the path of the starter lever to prevent operation of same when the ignition spark is advanced, vacuum operated means adapted to prevent operation of the starter lever when the engine is running and means to release the start lever when the ignition spark is retarded whereby to start the engine. 120

4. A gas engine controlling mechanism including a self-starter lever, a hollow body, locking means disposed within and recipro- 125

cable through said body across the path of the starter lever when the ignition spark is advanced to prevent starting of the engine, means to permit operation of the starting lever when the spark is retarded, and vacuum operated means adapted to move the locking means across the path of the starting lever to prevent operation of the same when the engine is running.

10 5. In a control for gas engine starters, a starter lever, a hollow body, vacuum actuated means disposed within said body, a bolt reciprocable through said body across the path of the starter lever by the vacuum actuated means when the engine is running, and means adapted to move said bolt across the path of the lever when the engine is idle upon the advancing of the ignition spark whereby to prevent starting of the engine

20 when the ignition spark is in the advanced position.

6. In a control for gas engines including a

self-starter lever, a reciprocable bolt, means whereby to automatically move said bolt across the path of the self-starter lever to prevent actuation of the same when the ignition spark is advanced and automatic means to move said bolt to an inoperative position to permit starting of the engine when the ignition spark is retarded.

25 7. A device of the character described, including a self-starter lever and an ignition controlling lever, locking means disposed between said levers adapted to move across the path of the starter lever to prevent operation of same when the ignition spark is advanced, automatic means adapted to prevent operation of the starter lever when the engine is running and means to release the starter lever when the ignition spark is retarded 30 whereby to start the engine.

35 In testimony whereof I affix my signature.

FAYE A. MEEKER.
